US00D850123S

(12) **United States Design Patent** (10) Patent No.: **US D850,123 S**
Enderby (45) Date of Patent: **** Jun. 4, 2019**

(54) **TISSUE SHEET WITH AN EMBOSSED PATTERN**

(71) Applicant: **CASCADES CANADA ULC**,
Montreal, Quebec (CA)

(72) Inventor: **Sandra A. Enderby**, New Franken, WI
(US)

(73) Assignee: **CASCADES CANADA ULC**,
Montreal (CA)

(**) Term: **15 Years**

(21) Appl. No.: **29/596,711**

(22) Filed: **Mar. 10, 2017**

(51) LOC (11) Cl. **05-06**

(52) U.S. Cl.

USPC **D5/26**; D5/62

(58) **Field of Classification Search**

USPC D5/1, 14, 20, 21, 26, 43, 46, 47, 52, 55,

(57) **CLAIM**

The ornamental design for a tissue sheet with embossing pattern, as shown and described.

DESCRIPTION

The sole FIGURE is a top plan view of a tissue sheet with embossing pattern, showing our new design.

The broken lines surrounding the FIGURE depict the boundaries of the claim and form no part thereof.

1 Claim, 1 Drawing Sheet
